UNITED STATES PATENT OFFICE.

GEORGE A. BOOMER, OF WATERBURY, CONNECTICUT, ASSIGNOR TO THE PLUME & ATWOOD MFG. CO., OF WATERBURY, CONNECTICUT, A CORPORATION.

ELECTRIC-LIGHTING FIXTURE.

Application filed July 19, 1926. Serial No. 123,357.

Fig. 1 is a plan view of my improved fixture;

Fig. 2 is a view thereof in side elevation;

Fig. 3 is a view thereof in vertical central 5 section on a larger scale; and

Fig. 4 is a view in side elevation, partly in section, of one of the modified forms which my improved fixture may assume.

My invention relates to improvement in 10 electric lighting fixtures, the object being to provide simple and efficient means for installing standard electric light socket-casings in shells, whether the same are designed for ceiling or side-wall fixtures.

15 With these ends in view, my invention consists in a fixture characterized by a housing-shell, a mounting-sleeve centrally installed therein, and adapted for the reception and seating of a socket-casing, and removable 20 means for locking the socket-casing upon a seat in the said sleeve.

25 My invention further consists in a fixture characterized as above and having certain details as will be hereinafter described and pointed out in the claim.

For the illustration of my invention, I have shown it as applied to a standard ceiling-canopy 10 provided with a standard shade-holder 11 permanently attached to the 30 said canopy by having its upper edge 12 turned inwardly, upwardly and outwardly over the inwardly-turned lip 13, forming the lower edge of the canopy. The joint thus formed produces an inwardly-extending annular ledge which serves for the installation 35 centrally within the said canopy 10 of a mounting-sleeve 14, formed near its lower end with an annular stop-shoulder 15 and an outwardly-turned, annular retaining- 40 flange 16, whereby the sleeve is rigidly secured in place within the canopy in upstanding position therein. Toward the upper end of the sleeve it is formed with an outwardly-extending, annular bead, producing an internal seating-shoulder 17 adapted in diameter 45 to form a seat for the lower edge 18 of the skirt 19 of the cap 20 of a standard socket-casing having a metal shell 21.

Above the seating shoulder 17 aforesaid, 50 the sleeve 14 is threaded for the application of a threaded locking-ring 22 having, at its upper end, an inwardly-turned retaining-flange 23 adapted in diameter to engage with

the upper edge 24 of the said skirt 19, so that, when the threaded locking-ring 22 is 55 screwed down upon the threaded upper end of the mounting-sleeve 14, the upper and lower edges of the skirt 19 are firmly gripped and held, whereby the socket-casing as a whole is firmly positioned within the 60 canopy 10, from which it is readily removed by simply removing the ring 22 from the open top of the canopy 10.

The pull-chain 25 of the socket-casing is 65 passed outward through a bushing in the canopy 10. For the accommodation of the pull-chain-bushing 26 in the socket-casing itself, the sleeve 14 is formed near its upper edge with a notch 27.

In the modified construction shown by 70 Fig. 4, the shade-holder 11 is omitted and the lower end of the sleeve 14 clamped directly upon the inwardly-turned lip 13 of the canopy 10. In this construction, the sleeve is formed with an annular inwardly-extending seating-shoulder 28, which 75 engages with the customary shoulder 29 of the shell 21 of the socket-casing, the shoulder 29 in this case being utilized, instead of the lower edge 18 of the skirt 19 of the cap 20. 80

It will be obvious from the foregoing that the supplemental mounting-sleeve 14, together with the locking-collar 22 or equivalent locking-means, may be applied to a side-wall shell, as well as to a ceiling canopy, 85 without departing from my invention. In either case, the shell or canopy forms a housing for the socket-casing.

I claim:

An electric lighting fixture having a housing-shell, a shade-holder secured thereto so as to form an inwardly-extending annular ledge, a mounting-sleeve having its lower end rigidly secured to the said ledge and provided, near its upper end, with a seating-shoulder for engagement with the edge of the skirt of the cap of a standard socket-casing, and also having its upper edge threaded, and a threaded locking-collar adapted to be applied to the threaded portion of the said sleeve and to engage with the upper edge of the skirt of the said cap, 90 whereby the casing is firmly held in place.

In testimony whereof, I have signed this specification.

GEORGE A. BOOMER.
